SPRAY NOZZLE

Fred W. Wahlin, Chicago, Ill., assignor to Spraying Systems Co., Chicago, Ill., a corporation of Illinois

Application March 22, 1940, Serial No. 325,381

2 Claims. (Cl. 299—114)

My invention relates to nozzles for spraying liquids in a hollow cone or parasol form and has reference more particularly to facilities for equalizing and directing the spray.

It is a common practice to employ spray nozzles wherein liquid is introduced tangentially into a circular chamber to impart rotation thereto and to discharge the rotating liquid through an axially disposed orifice so as to spray the liquid in a hollow conical or parasol form.

It is important that the liquid discharge from the orifice in a uniform or balanced hollow cone or parasol form so as to insure equalized and uniform range and distribution of the liquid spray about the axis of the orifice but this is difficult to accomplish because the whirling impulse is imparted to the liquid in the chamber at one side thereof and this tends to disturb the symmetry of the whirling body of liquid in the chamber and impart peripheral inequalities or variations in liquid flow through the orifice. Moreover such nozzles are required to be made with various spray angles so as to afford any desired spread, including parasol and flat circular forms of spray, and it is important that the liquid should discharge accurately from the nozzle in the proper direction to produce the particular form of spray desired.

The principal objects of my invention are to provide a spray nozzle of hollow cone, parasol or flat circular spray type in which a uniform symmetrical spray is assured; to accomplish such uniformity and symmetry of spray by a simple and convenient internal shaping of the nozzle chamber; to provide an improved parasol or flat circular spray nozzle in which the direction of discharge may be accurately controlled; and in general to provide an improved spray nozzle in a simple, compact and inexpensive form, these and other objects being accomplished as pointed out hereinafter and as shown in the accompanying drawing, in which:

Fig. 1 is a view looking at the top of a spray nozzle constructed in accordance with my invention with a portion thereof in section on the line 1—1 of Fig. 2.

Fig. 2 is a sectional view of the spray nozzle of Fig. 1 taken on the line 2—2 of Fig. 1;

Fig. 3 is a view, similar to Fig. 1, of another form of spray nozzle;

Fig. 4 is a sectional view on the line 4—4 of Fig. 3; and

Figs. 5 and 6 are sectional views of modified forms of the spray nozzles of Figs. 1 and 3 respectively.

Referring to Figs. 1 and 2, the spray nozzle shown therein is of conventional form in the respect that it comprises a body 11 with a circular whirl chamber 12 therein into which an inlet passageway 13 leads tangentially so as to impart rotary or whirling movement to the liquid in the chamber 12, the body 11 having at one side of the whirl chamber 12 and concentric therewith a threaded opening 14, preferably of the same diameter as the chamber 12, with a threaded plug 15 therein which has a nozzle opening 16 therethrough axially aligned with the whirl chamber 12.

The nozzle opening 16 has a cylindrical mouth portion 17 of a diameter preferably slightly smaller than the diameter of the inlet passageway 13 and flares inwardly as indicated at 18 and 19 to the whirl chamber 12 and as the liquid enters the chamber 12 from the inlet passageway 13 it is whirled in the chamber 12 and expelled outwardly through the nozzle opening 16 in a centrally open rotating (see dotted lines 20) annular stream at sufficient axial velocity to form a thin hollow conical spray substantially as indicated at 21 in Fig. 2. At the outer end of the inlet passageway 13, the body 11 may be formed with any convenient means, such for example, as the external threads 22 for connection to piping or the like through which liquid is supplied to the spray nozzle.

Because of the tangential entry of the liquid into the chamber 12 and the whirling impulse thus imparted to the liquid at one side of the said chamber, irregularity or non-uniformity of liquid discharge around the orifice 17 ordinarily occurs which is quite objectionable as it results in a non-symmetrical or unbalanced spray 21.

I have found, however, that by forming the whirl chamber 12 at the side remote from the nozzle outlet with a cavity 23 of relatively large diameter in axial alignment with the whirl chamber 12 and outlet 16 and with an abrupt shoulder 24 therearound, this corrects the inequalities or non-uniformity of liquid discharge around the orifice 17 and insures a balanced symmetrical hollow conical spray 21. Such correction chamber or cavity 23 may be relatively shallow as shown which is advantageous as it permits construction of the spray nozzle in a small compact form.

Instead of employing an apertured plug as in Figs. 1 and 2 through which the liquid is discharged, the nozzle may be made as in Fig. 5 with the discharge opening through a wall of the nozzle body 25 as indicated at 26 and the oppo-

site side of the whirl chamber 27 may be closed by a solid plug 28 and the latter formed at the inner end with the correction or equalizing chamber or cavity 29 which serves the same purpose as the chamber or cavity 23 of the structure of Figs. 1 and 2. While the form of correction chamber shown at 23 in Figs. 1 and 2 with the surrounding wall thereof curving inwardly and downwardly from the shoulder 24 to the chamber bottom is preferred, the correction chamber may be made of shallow cylindrical form as shown in Fig. 5 and the whirling chamber may also be cylindrical as shown at 27 in Fig. 5. An inlet passageway 30 leads tangentially into the whirl chamber as in the structure of Figs. 1 and 2 and at the outer end of this inlet passageway 30 the body 28 is formed for pipe connection therewith, as for example with internally threaded opening 31.

Figs. 3 and 4 show a spray nozzle for parasol or extremely wide angle spray, in which the body 32 is formed with a whirl chamber 33 and provided with a discharge outlet 34, both of which are of much larger diameter in comparison with the inlet passageway 35 thereof than in the structure of Figs. 1 and 2, the margin of the outlet 34 being curved outwardly as at 36 to provide a mouth with gradually increasing outward flare terminating in a flat conical outer face 37 which serves to direct the discharged liquid accurately in the selected direction of wide angle or parasol spray.

The inlet passageway 35 leads tangentially into the whirl chamber 33 as in the previously described structure to impart to the liquid in the chamber 33 a whirling or rotary movement so that the liquid flows to the outlet 34 in a hollow annular stream as shown by the dotted lines 38 in Fig. 4. The diameter of the chamber 33, as well as that of the outlet 34, is large in proportion to the diameter of the inlet passageway 35 to give the rapidly whirling liquid in the chamber 33 a slow enough outward or axial velocity so that the centrifugal force of the whirling liquid is sufficiently greater than the outward or axial velocity to cause the issuing liquid to follow the curvature 36, 37 of the outlet and discharge radially around the outlet in a parasol or flat spray form as indicated at 39 corresponding to the pitch or flatness of the surface 37. Thus the surface 37 serves as a guide which controls the direction of discharge of the liquid and by changing the pitch of the surface 37 the direction of discharge may be varied.

In practice, I have found that the cross sectional area of the chamber 33 should be not less than approximately eight or more times the cross sectional area of the inlet passageway 35 and the outlet 34 should be large enough not only to avoid axial velocity which would interfere with or impair the centrifugal discharge but also to form an issuing stream of liquid of sufficient diameter to have ample centrifugal force to insure positive discharge of the liquid radially along the guide surface 37 and therebeyond to the desired spray range.

This spray nozzle, like those of Figs. 1 and 2, is provided with a shallow correction chamber or cavity 40 at the side of the whirl chamber 33 remote from the outlet 34 which said chamber or cavity 40 has an abrupt shoulder 41 therearound and is in axial alignment with the whirl chamber 33 and outlet 34 and it is to be noted that in this structure, as well as that of Figs. 1 and 2, the correction chamber extends at one side part way

across the adjacent path of the stream of liquid entering through its tangential inlet. By reason of this correcting or equalizing chamber 40 the unbalancing of liquid flow due to the injection of liquid tangentially into the chamber 33 is counteracted and the outflow of liquid at all places around the outlet 34 is equalized and a balanced, uniform spray 39 is assured.

The spray nozzle body 32 is formed at the outer end of the inlet passageway with any desired form of connection by which a pipe or duct may be attached to supply liquid to the passageway 35, an internally threaded opening 42 being shown herein for purposes of illustration.

Preferably the outlet opening 34 is formed in a ring 43 which is pressed tightly into a seat 44 provided therefor in the wall of the body 32 at the side of the whirl chamber 40 as shown in Fig. 4. However, since the size of the opening 34 is such that a tool may be inserted therethrough to form the chamber 33 and cavity 40, the spray nozzle may be of one piece construction as shown in Fig. 6. In this figure the parts thereof corresponding to those of Fig. 4 have the same reference numerals applied thereto and it will be noted that the ring 43 of Fig. 4 is omitted and instead the body 32 is formed with an internal annular shoulder 45 surrounding the outlet 34 and shaped at 36 and 37 like the ring 43 of Fig. 4, the internal surface of the whirl chamber 33 being flared inwardly as indicated at 46 to the maximum diameter of the whirl chamber as clearly shown in Fig. 6.

In the operation of these spray nozzles the liquid is introduced under pressure through the respective tangential inlet passageway 13, 30 or 35 and imparts a whirling movement to the liquid in the respective chamber 12, 27 or 33 and as liquid continues to be supplied, it is forced outwardly through the respective opening 16, 26 or 34. In each case the liquid issues through the respective opening in a hollow whirling stream which, by reason of the respective correction chamber 23, 29 or 40 is equalized or uniform around the respective opening. Because of the size relationship of the outlets 16 and 26 to their respective whirl chambers 12 and 27 and their respective inlets 13 and 30, the axial velocity of the liquid through the outlets 16 and 27 is such with relation to the centrifugal force of the whirling stream that the liquid discharges in the form of a hollow cone substantially as shown at 21 in Fig. 2.

In the structures of Figs. 4 and 6, however, the size relationship of the outlet 34 and whirl chamber 33 to the inlet 35 is such that the centrifugal force of the whirling stream of issuing liquid sufficiently exceeds the axial velocity, that the issuing liquid hugs the curved flaring surfaces 36 and 37 and the liquid is thus discharged in the flat conical or parasol form 39 in a direction determined by the flatness or pitch of the guiding surface 37.

While I have shown and described my invention in a preferred form, I am aware that various changes and modifications may be made therein without departing from the principles of my invention, the scope of which is to be determined by the appended claims.

70 I claim as my invention:

1. A spray nozzle comprising a body having therein a circular chamber with a discharge outlet at one side and a relatively wide shallow circular cavity at the other side both axially aligned with said chamber, said chamber having an in-

let passageway leading thereto tangentially to inject liquid into the chamber and impart rotation thereto and discharge same from the outlet in a hollow annular stream, said cavity having at its juncture with the chamber a surrounding shoulder constructed and arranged to annularly equalize outflow of liquid through the discharge outlet.

2. A spray nozzle comprising a body having therein a circular chamber with a discharge outlet at one side and a relatively wide shallow circular cavity at the other side both axially aligned

5 with said chamber, said chamber having an inlet passageway leading thereto tangentially to inject liquid into the chamber and form therein an annular rotating body of liquid which is progressively discharged from the outlet in a hollow annular stream, said cavity being of a width to extend at one side part way across the annular zone of rotation of the liquid in the chamber, said cavity being constructed and arranged to annularly equalize outflow of liquid from the chamber through the discharge outlet.
